(57) **CLAIM**

I claim the ornamental design for a container closure, as shown and described.

DESCRIPTION

FIG. 1 is a top view of a container closure showing the new design;

FIG. 2 is a bottom view thereof;

FIG. 3 is a top perspective view thereof;

FIG. 4 is a bottom perspective view thereof; and,

FIG. 5 is a front elevation view with the right side, left side and rear views all being identical.

1 Claim, 3 Drawing Sheets

FIG. 1

FIG. 2

FIG. 3

FIG. 4

FIG. 5
